UNITED STATES PATENT OFFICE.

CONRAD HENRY MATTHIESSEN, JR., OF NEW YORK, N. Y.

SLIDE-VALVE MECHANISM FOR INTERNAL-COMBUSTION ENGINES.

Application filed November 26, 1923, Serial No. 676,991, and in Great Britain October 31, 1923.

My invention relates to a slide valve mechanism for internal combustion engines of the four cycle type and more particularly to improvements in the invention illustrated 5 in my copending application Serial No. 440,573, filed January 28th, 1921, for slide valves for gas engines.

One of the objects of my invention is to produce effective mixing of the gas as it 10 flows into the top of the explosion chamber, to do away with deflectors in the path of the incoming gas and to do away with gas corridors for discharging products of combustion and for supplying gas to the ports, 15 thus improving the cooling and the lubrication. Another object is to provide an efficient oiling system for a sliding plug and sleeve valve mechanism and particularly for the plug and sleeve valve mechanism illustrated 20 in my copending application above referred to.

Another object of my invention is to provide a bottle liner whose body forms the explosion chamber and whose neck forms the 25 valve chamber within which neck plug and sleeve reciprocate. The liner is spaced from the engine casing so as to form a water jacket and is shrunk or secured to the casing at the neck leaving the body free to 30 expand—thus permitting the use of different metals for the liner and casing. The combustion chamber is sealed by the plug and sleeve at the valve end and by the working piston at the other.

With the above and other objects in view 35 my invention consists in the parts, improvements and combinations more fully pointed out hereinafter.

Referring now to the drawings, illustrating 40 one form of the invention:

Figure 1 is a longitudinal section showing my improved valve mechanism with the sleeve about to begin the inlet stroke, the exhaust being closed and the interior discharge mouth of the inlet passage of the sleeve being open.

Figure 2 is a section showing the parts 45 toward the middle of the inlet stroke.

Figure 3 shows the diaphragm joint between the lower end of the bottle liner and the engine casing, permitting expansion of the liner.

Figure 4 shows the valve driving speed reduction gearing.

Figures 5, 6, 7 and 8 illustrate the posi-

tion of the parts at the full open position of the intake, at the middle of the compression, the firing point and the exhaust open respectively.

Figure 9 illustrates the inlet passages in 60 the liner and casing, and

Figure 10 illustrates the sleeve with its ports and oil grooves.

The valve is mounted at the top of the head of the cylinder 1, preferably in line 65 with the axis of the cylinder in a throat which is preferably narrower than the bore of the cylinder, thus reducing the size of the parts. The cylinder, in accordance with the invention forms a bottle shaped liner and 70 valve chamber, having a body 2, forming the explosion chamber, the coaxial neck 3 of the bottle forming the valve chamber in which the valve reciprocates. The neck of the bottle may thus be inserted within and shrunk 75 or secured to the water jacketing portion 4 of the valve containing head of the engine casing 5, leaving the body of the liner free to expand, thus permitting the use of different metals for casing and liner, the latter 80 for example being of iron or steel and the former of aluminium alloy. The end of the bottle is sealed to the casing 5, to prevent water jacket leakage, by diaphragm 6 and bolts 7, so that when heated or cooled it may 85 slide slightly with relation to the casing. The space 7^a between the bottle and the casing forms a water jacket for the body of the bottle which latter constitutes the combustion chamber and the bore for the working piston. The bottle liner may be cast and machined to any desired wall thickness 90 throughout its length so that at the combustion chamber, the walls are of uniform 95 thickness avoiding unequal distribution of metal around the combustion chamber and resulting in more uniform cooling.

In accordance with my invention, the water jacketed valve containing head is provided 100 with two diametrically opposite inlet passages 8, 9, which extend partly around the valve containing head, thus producing effective mixing of the gases, and an exhaust passage 10. I also provide a single sleeve 105 valve 11, with an inlet port which consists of two openings 12, 13 oppositely arranged. The two ports 12^a and 13^a in the bottle liner and 8, 9 in the cylinder casting itself may be accurately machined from the out- 110

side of the casting by the usual tools, after assembly of the bottle and the casting. The ports extend circumferentially and the metal between them gives a substantial support to the upper part of the bottle and forms the water cooled portion which carries the rings across the port openings. The same principle applies to the sleeve. In the sleeve, the ports also extend circumferentially and the metal between the ports is water cooled by means of the adjacent water jacketed portion of the head of the casing, containing the valve. By thus doing away with gas corridors around the valve containing head, which gas corridors feed a belt of inlet ports and by bringing the cooling surfaces next to the sleeves more effective cooling and better lubrication are obtained. Suitable means are provided for driving the sleeve. As illustrated, the sleeve is driven from an overhead valve shaft 14 by a two to one speed reduction gearing from the main crank shaft 14^a of the engine by gearing 14^b, 14^c, 14^d, 14^e, the sleeve being connected to the overhead shaft by suitable means such as a connecting rod 15. As indicated, the connecting rod is secured to the sleeve by suitable means for example by means of a pivot. The sleeve is cut away at its upper part as shown so as to permit the end of the connecting rod for the plug to pass within the sleeve and bring the rod bearing nearly in line with the center of pressure. In accordance with my invention, I make the height of the inlet mouth of the sleeve (measured in the direction of the length of the sleeve) and its cross-section greater than the height and cross-section of the inlet passage. By this means, the inlet mouth of the sleeve moves into and out of registering relation with the inlet passage in the valve head liner and remains in registering relation therewith for a substantial part of the stroke of the sleeve. This ensures a full opening of the inlet and a plentiful supply of gas during a large part of the inlet stroke. By lessening the height of the supply passage in the valve containing head I lessen the height of the valve containing head and reduce the height of the inlet ports.

The sleeve is provided with a skirt 16 which opens and closes the exhaust passage 10. The inlet port controls the inlet and does not move into registering relation with the exhaust passage, the exhaust passage being controlled by the skirt 16. Rings 17 are used for securing a gas tight fit between the sleeve and the valve seat or throat in which the sleeve moves.

Turning now to the plug 18, this also is driven in the form of invention illustrated, from the valve shaft 14. A connecting rod 19 connects the plug with the valve shaft, the connecting rod being pivotally secured

to the plug. The plug is provided with one or more rings 20 seated in a groove in the plug.

Means are provided for oiling the valve and plug without permitting the oil to reach the combustion chamber. Oil drops or is supplied from above as from the valve shaft to the cup shaped top of the sleeve. Excess oil is taken off by the respective oil rings 21, 22 on plug and sleeve scraping the oil into the two sets of oil holes 23, 24. The ring 21 in the upper part of the plug scrapes the excess oil into the oil holes 23 in the upper part of the sleeve. As shown in Figures 2 and 5 the excess oil passes into the head 100 of the engine casing from which it discharges to the crank case. The remainder of the oil works down between the sleeve and bottle liner and any excess is scraped by the upper ring 22 of the sleeve into oil holes 24 in the bottle liner, where the excess drains off on slanting head 25, and is discharged to the crank case, leaving oil to lubricate between sleeve and plug and sleeve and bottle liner, without it passing into the combustion chamber. By means of grooves 25^a, 25^b arranged in the metal of the sleeve between the sleeve ports and starting from a point in the sleeve below ring 22, oil is carried to the lower or skirt part of the sleeve.

It will be seen by an inspection of the Figures 1, 2, 5, 6, 7 and 8 that the plug is out of the way of the inlet port during the inlet stroke and that it acts during the compression and firing strokes to prevent the gases from being forced back from the combustion chamber of the engine through the inlet port of the sleeve. In Figures 2 and 5, the oil ring 21 on the plug is shown in a position to discharge oil through ports 23, 24. In Figure 8, the oil ring 22 is shown in position for discharging oil thru the ports 24.

Spark plugs are inserted at projections 26, 27, carried by the bottle and suitable bushings 28, 29 are provided to seal the openings in the casing so as to prevent the escape of water.

Having thus described my invention, it will be understood that changes may be made therein without departing from the principle of the invention.

What I claim and desire to secure by Letters Patent is:

1. An internal combustion engine of the four cycle type, comprising a valve containing head, a sleeve slide valve reciprocating therein, said valve provided with a port whose lips open and close the inlet passage in the valve containing head, said valve having a skirt portion controlling the exhaust, and a movable member within the sleeve for blocking the port in the sleeve during the compression and firing strokes, said sleeve valve and valve containing head being provided with oil holes, the movable member

and the sleeve valve being provided with rings cooperating with said oil holes, thereby distributing the feeding of the oil through the valve mechanism.

5 2. An internal combustion engine of the four cycle type, comprising a valve containing head, a sleeve slide valve reciprocating therein, said valve provided with a port whose lips open and close the inlet passage 10 in the valve containing head, said valve having a skirt portion controlling the exhaust, and a movable member within the sleeve for blocking the port in the sleeve during the compression and firing strokes, 15 said sleeve valve and valve containing head being provided with oil holes, the movable member and the sleeve valve being provided with rings cooperating with said oil holes, thereby distributing the feeding of the oil 20 through the valve mechanism, said sleeve member provided with oil grooves to supply oil to the skirt portion of the sleeve valve.

3. An internal combustion engine of the four cycle type, comprising a valve containing head, a sleeve slide valve reciprocating therein, said valve provided with an inlet port and a movable member within the sleeve valve, said valve containing head and sleeve valve being provided with oil holes 25 and said movable member and sleeve valve being provided with rings cooperating with said oil holes to distribute flow of oil through the valve mechanism.

4. An internal combustion engine of the four cycle type, comprising in combination 30 an engine casing, a longitudinal valve containing head, a sleeve slide valve reciprocating therein, said valve provided with an inlet port, a movable plug within the sleeve valve, a longitudinally expandable liner for said casing, said liner consisting of a bottle forming the cylinder and a longitudinal neck forming its extension, the neck of the bottle forming the valve chamber in which the 35 valve and plug reciprocate, said neck being secured to said valve containing head and an expansion joint for securing the lower end of the liner to the casing, thereby permitting the body of the liner to expand.

50 5. An internal combustion engine of the four cycle type, comprising in combination 45 an engine casing, a valve containing head, a sleeve slide valve reciprocating therein, said valve provided with an inlet port, a movable plug within the sleeve valve, a longitudinally expandable liner for said casing, said liner consisting of a bottle forming the cylinder and its extension, the neck of the bottle forming the valve chamber in which the 55 valve reciprocates, and an expansion joint for securing the lower end of the liner to the casing, said expansion joint comprising a diaphragm attached to the liner and means for securing the diaphragm to the 60 casing.

6. An internal combustion engine of the four cycle type, comprising in combination 65 an engine casing, a longitudinal valve containing head, a sleeve slide valve reciprocating therein, said valve provided with an inlet port, a movable plug within the sleeve valve, and a liner for said casing, said liner consisting of a bottle forming the cylinder and a coaxial longitudinal neck forming its extension, the neck of the bottle forming the 70 valve chamber in which the valve and plug reciprocate, said neck being shrunk upon said valve containing head, said liner being spaced from the engine casing so as to provide a water jacket between the casing and liner, the body of the liner being free to expand.

7. An internal combustion engine of the four cycle type comprising in combination 75 an engine casing, a valve containing head, a sleeve slide valve reciprocating therein, said valve provided with an inlet port, a movable plug within the sleeve valve, and a liner for said casing, said liner consisting of a bottle forming the cylinder and a coaxial 80 longitudinal neck forming its extension, the neck of the bottle forming the valve chamber in which the valve reciprocates, said neck being secured to said valve containing head, said liner being spaced from the engine casing so as to provide a water jacket between the casing and the liner, the liner being provided with apertured projections for receiving the spark plugs, and means for sealing the openings in the casing so as to prevent 85 the escape of water, comprising perforated bushings through which the spark plugs pass, said bushings fitting the projections on the bottle liner which receive the spark 90 plugs and also engaging the casing.

8. An internal combustion engine of the four cycle type, comprising in combination 95 a valve containing head, said valve containing head provided with opposite inlet passages extending only partly about the head, a sleeve slide valve reciprocating therein, said sleeve valve provided with two inlet ports oppositely arranged and each extending only partly around the valve containing head so as to produce effective mixing of 100 the gases, said sleeve valve having a skirt portion controlling the exhaust, and a movable member within the sleeve for blocking the port in the sleeve during the compression and firing strokes.

9. An internal combustion engine of the four cycle type, comprising in combination 110 with a valve containing head, said valve containing head provided with opposite inlet passages extending only partly about the head, a sleeve slide valve reciprocating therein, said sleeve valve provided with two inlet ports oppositely arranged and extending only partly around the valve containing head so as to produce effective mixing of 115 120 125 130

4
the gases, a water jacket adjacent to said sleeve valve, said valve having a skirt portion controlling the exhaust, and a movable member within the sleeve for blocking the port in the sleeve during the compression and firing strokes.

10. An internal combustion engine of the four cycle type, comprising in combination a valve containing head, said valve containing head provided with opposite inlet passages extending only partly about the head, a sleeve slide valve reciprocating therein, said sleeve valve provided with two inlet ports oppositely arranged and extending

only partly around the valve containing head so as to produce effective mixing of the gases, a movable plug within the sleeve valve and a liner secured to said valve containing head, said liner consisting of a bottle forming the cylinder and its coaxial 15 neck, the neck of the bottle forming the valve chamber in which the valve reciprocates, said liner provided with two ports oppositely arranged so as to register with the ports in the sleeve.

15
